UNITED STATES PATENT OFFICE.

EDGAR WEBSTER SUMMERS, OF PITTSBURGH, PENNSYLVANIA.

TRUCK SIDE FRAME AND JOURNAL-BOX.

1,189,636.

Specification of Letters Patent.

Patented July 4, 1916.

Application filed November 3, 1915. Serial No. 59,403.

To all whom it may concern:

Be it known that I, EDGAR W. SUMMERS, a resident of Pittsburgh, in the county of Allegheny and State of Pennsylvania, have invented a new and useful Improvement in 5 Truck Side Frames and Journal-Boxes, of which the following is a specification.

This invention relates to side frames for railway car trucks and journal boxes 10 therefor.

One object of the invention is to provide a railway car truck side frame of the arch bar type and a journal box so constructed that the neutral axes or centers of gravity of the tension and compression members of the truck side frame intersect vertically over the axis of rotation of the axle and as close down to the same as possible.

Another object is to provide an emergency connection between the journal box and side frame so arranged as to permit a wide bearing of the side frame on the journal box, and at the same time not interfere with the attachment and proper opening of the usual 25 Master Car Builders' lid.

Another object of the invention is to provide such a construction of column posts connecting the compression and tension members as to prevent bending stresses in the 30 tension member due to the upward lift of the bowed or arched compression member.

The invention comprises the construction and arrangement of parts hereinafter described and claimed.

In the accompanying drawings, Figure 1 is in part a side elevation and in part a longitudinal vertical section of a truck side frame embodying the invention, showing the journal box attached thereto; Fig. 2 is in part a plan view of the same and in part a horizontal section on the line 2-2, Fig. 1; Fig. 3 is a vertical transverse section on the line 3-3, Fig. 1; Fig. 4 is a plan view of the pedestal jaw member; Fig. 5 is in part an end elevation of the same and in part a vertical section of the same on the line 5-5, Fig. 4; Fig. 6 is a vertical transverse section of the same on the line 6-6, Fig. 5; Fig. 7 is a similar section on the line 7-7, Fig. 5; Fig. 8 is a plan view of the journal box; Fig. 9 is a vertical longitudinal section through the same on the line 9-9, Fig. 8; Fig. 10 is an elevation of the inner end of the journal box; and Fig. 11 is a transverse vertical section through the same on the line 11-11, Fig. 8.

The truck side frame illustrated is of the arch bar type having an upwardly bowed or arched compression member 1 and a downwardly bowed tension member 2, the latter having its central portion, as at 3, formed on the arc of a circle or catenary curve, and with the end portions extending from said curved portion as true tangents. As illustrated, the tension and compression members are formed of rolled flanged sections, the specific sections illustrated being I-beams placed with their webs horizontal and their flanges vertical. At their end portions some of the flanges of these members are cut away so as to permit the webs to come into contact, and said members are secured together by rivets 5 extending through said webs. In the angle between the compression and tension members are placed gusset members 6 shown as castings, although they may, if desired, be pressed plates or forgings, and which are secured to the tension and compression members by rivets 7. The end portions of said tension and compression members, beyond the point 8 of intersection of their neutral axes or centers of gravity, are bent downwardly so as to lie at the same angle from the vertical as the inclined portion of the tension member 2, thereby forming on the lower face of the end portion of the side frame an upwardly converging obtuse angle, as shown in Fig. 1. Fitting in this angle is the pedestal jaw member 10 which comprises a pair of web portions 11 oppositely inclined relatively to each other and fitting against the lower faces of the web of the tension member 2 on opposite sides of the point of intersection of the neutral axes of the tension and compression members, and provided with holes for receiving rivets by means of which said member is secured to the side frame. As shown, the same rivets which secure the tension and compression members together at their outer ends and those which secure the gusset members 6 to the tension member, also serve the purpose of securing the pedestal jaw member 10 to the side frame. The web member 11 toward the center of the truck side frame has an extension 12 for receiving one of the rivets which is used to secure the gusset member 6 to the tension member. The web portions 11 of the member 10 are provided on both sides with grooves 13 for receiving the downwardly extending flanges of the tension member, and outside of these are the

vertical webs or flanges 14 extending upwardly and embracing the side faces of the side frame and beaded at their upper edges, as at 15, for strength. These flanges also 5 extend downwardly and form the pedestal jaws 16 which are of material width side- wise of the frame, and which flare or diverge downwardly, as shown in Figs. 1 and 5, and which are adapted to receive the journal box 10 17, as shown. The pedestal jaws 16 are symmetrically arranged with reference to the vertical transverse plane of the pedestal jaw member, and as the latter fits up in the angle formed on the lower face of the side 15 frame, it necessarily follows that the center of rotation of the axle 18 is directly vertically below the point of intersection 8 of the centers of gravity of the tension and compression members of the side frame.

20 The journal box 17 at its central zone has the upper portion of its side walls beveled upwardly and inwardly, as shown at 19, on an angle corresponding to the inclination or flare of the pedestal jaws, as a result 25 of which the journal box fits high up into the pedestal jaw member and thus reduces to a minimum the vertical distance between the axis of rotation of the axle and the point of intersection of the neutral axes 30 of the tension and compression members. At the same time such beveled off portions of the side wall do not interfere in any way with the dimensions of the box to receive the standard Master Car Builders' wedge 20 35 and brass 21. The box on its interior is provided with the usual lugs 22 for holding the brass, and the efficiency of this lug is not interfered with by beveling off the side walls toward the top, as these bevels merely 40 move metal from a place where it performs no useful function.

Outside or forwardly of the central beveled portions 19 the journal box is of substantially square contour at the top, as 45 shown at 24, and is provided with the usual lugs 25 for receiving a lid 26 of the Master Car Builders' type. Inwardly of the beveled portion 19 the top of the box is also of square contour, as shown at 27, and is provided with the usual dust guard pocket 28. To prevent breakage of the inner wall 29 of the dust guard pocket by endwise blows 50 of the wheel hub, the box is provided with buffers or abutments 30 preferably cast integral therewith and placed on diametrically opposite sides and in line longitudinally with the side walls of the box, and which project inwardly sufficiently far to receive the impact of the wheel hub and prevent the 55 latter from striking the wall 29, and since these abutments are in direct line with the side walls of the box, the stresses of such endwise blows are carried directly into the side walls of the box, where they do no 60 damage. Preferably these abutments 30 are

braced at their central portions by bracing webs 31.

To provide an emergency connection between the journal box and truck side frame and prevent the box from displacement in 70 case of wrecks or other emergencies, the pedestal jaw member is provided with a pair of horizontal perforated ears or lugs 33 and the journal box is provided with a pair of vertical perforated ears or lugs 34, 75 which pairs of ears or lugs receive a connecting pin 35, which, however, need have only a relatively loose fit and serves no purpose other than to prevent the accidental displacement of the journal box relative to 80 the side frame. The ears or lugs 33 and 34 are spaced wide apart, as shown in Figs. 2 and 8, much farther apart than the lugs of the lid 26, so that this emergency connection does not interfere with the proper opening of the lid, and at the same time allows of a very broad side frame bearing on the journal box. Heretofore where such emergency connections have been provided between the side frame and the journal box, 85 it has been by means of lugs located at the center of the journal box, in exactly the same longitudinal plane as the lid lugs, which has required a narrow bearing of the truck side frame on the journal box in order to 90 provide sufficient space between the lid lugs and the emergency securing lugs to permit the lid to open. By spacing the emergency securing lugs apart laterally of the box, as in the present design, they do not interfere 95 with the proper opening of the lid and at the same time permit of a very wide bearing of the side frame on the journal box, which is of material importance, as the strains are thus distributed over a much 100 wider area or zone on the journal box as compared with the prior constructions.

By having the journal box beveled off at its central zone and fitting up between the flaring pedestal jaws, it enables the end of 110 the side frame to be brought low down relative to the axle, thus increasing the stability and avoiding objectionable height of the truck side frame.

The compression and tension members at 115 their central portions are united by a column post member which comprises in a single integral casting the vertical column post portions 37, the bottom spring seat portion 38 and a top connecting portion 39. The top 120 connecting portion 39 fits against the web of the compression member and is secured thereto by rivets 40. By having an integral connecting portion 39, all blows of the bolster longitudinally of the trucks are resisted by all of the rivets 40, no matter in which direction the blows may take place. The spring seat portion 38 is formed on an arc fitting the web of the curved central portion 8 of the tension member and is se- 125 130

cured thereto by rivets 41. Spring plank members 42 are secured to this casting, such as by bolts 43, and the springs 44 rest directly on the bottom portion 38. The column post portions 37 are provided with the usual bolster guides 45 and brake hanger brackets 46.

In arch bar trucks in which the compression member is bowed or arched upwardly the stresses induced by the load exert a tendency to arch or bow said compression member still further upwardly, as a result of which the column posts exert a lifting tendency, which with ordinary constructions is transferred into the tension member and thence to the spring seat, with the result that there is a tendency to bend or deflect the tension member upwardly at the points where the lower ends of the column posts are attached thereto. This induces compression stresses in the lower face of the tension member at these points, which compression stresses neutralize to some extent the tension stresses in the member, with the result that the effective area for resisting the tension stresses is reduced. Some forms of arch bar truck side frames have failed at these points due to this cause. By forming the seat integral with the column posts, as in the present construction, the upward lift on the posts due to the tendency of the arched compression member to bow still further upwardly, is transferred directly to the spring seat, and does not have to go into the tension member at all. As a consequence there is no tendency to deflect the tension member upwardly at the points where the lower ends of the column posts are attached thereto. This effect is also aided from the fact that the central portion of the tension member is on the arc of a circle and the inclined end portions are tangent thereto. The result of the structure is that there are not opposed neutralizing stresses in the tension member, but the entire cross sectional area of the latter is effective to resist the tension stresses and there is not the danger of failure as in the prior constructions.

What I claim is:

- 1. A truck side frame of the arch bar type comprising a compression member and a tension member having their end portions secured together and with their centers of gravity intersecting, pedestal jaw members secured to said end portions, the jaws of said members converging upwardly, and journal boxes having portions of their side walls near the top beveled and inclined upwardly and inwardly and fitting between said pedestal jaws, whereby the intersection of the centers of gravity of the side frame members are brought vertically over the center of rotation of the axle and close down to the tops of the journal boxes.
  - 2. A truck side frame of the arch bar type comprising a compression member and a tension member formed of flanged sections placed with their webs horizontal and the flanges vertical and having their end portions formed to bring the webs into contact and being secured together through said webs, and having their end portions outside of the point of intersection of their neutral axes bent downwardly on an angle corresponding to the inclination of the tension member, a pedestal jaw member se- 130
- comprising a compression member and a tension member formed of flanged sections placed with their webs horizontal and the flanges vertical and having their end portions formed to bring the webs into contact 70 and being secured together with their centers of gravity intersecting, pedestal jaw members secured to said end portions, the jaws of said members converging upwardly, and journal boxes having portions of their side walls at the top beveled upwardly and inwardly and fitting between said pedestal jaws, whereby the intersection of the centers of gravity of the side frame members are brought vertically over the center of rotation of the axle and close down to the tops 75 of the journal boxes.
3. A truck side frame of the arch bar type comprising compression and tension members united at their ends and having their end portions outside of the point of intersection of their centers of gravity inclined downwardly at an angle corresponding to the inclination of the tension member, a pedestal jaw member fitting in said angle 80 and secured to the side frame and having downwardly flaring diverging jaws, and a journal box having its central zone beveled upwardly and inwardly and fitting between said flaring jaws, whereby the intersection 85 of the centers of gravity of the side frame members is brought vertically over the center of rotation of the axle and close down to the top of the journal box.
4. A truck side frame of the arch bar type comprising a compression member and a tension member having their end portions parallel and secured together and having their end portions outside of the point 90 of intersection of the neutral axes of the tension and compression members bent downwardly on an angle corresponding to the inclination of the tension member, a pedestal jaw member secured in said angle 95 and provided with downwardly flaring or diverging jaws, and a journal box having its central zone inclined upwardly and inwardly and fitting between said jaws, whereby the intersection of the neutral axes 100 of the tension and compression members is 105 brought vertically over the center of rotation of the axle and close down to the top of the journal box.
5. A truck side frame of the arch bar type comprising a tension member and a compression member formed of flanged sections placed with their webs horizontal and the flanges vertical and having their end portions formed to bring the webs into contact 110 and being secured together through said webs, and having their end portions outside of the point of intersection of their neutral axes bent downwardly on an angle 115 corresponding to the inclination of the tension member, a pedestal jaw member se- 120

4
cured in said angle and provided with downwardly flaring or diverging jaws, and a journal box having its central zone beveled or inclined upwardly and inwardly 5 and fitting between said diverging jaws, whereby the intersection of the neutral axes of the side frame members is brought vertically over the center of rotation of the axle and close down to the top of the journal box.

10 6. A truck side frame of the arch bar type provided with pedestal jaws, a journal box fitting between said pedestal jaws, said side frame having a broad contact lengthwise of said journal box, a pair of widely spaced horizontal lugs on said side frame, a pair of coöperating vertical lugs on said journal box, and emergency means connecting said lugs.

15 7. A truck side frame of the arch bar type, a pedestal jaw member secured to the ends of said side frame and provided with a pair of widely spaced perforated lugs, a journal box fitting said pedestal jaws and 20 provided with a pair of coöperating perforated lugs, and having a broad contact lengthwise thereof with the side frame and a pin connecting said pairs of perforated lugs.

25 8. A truck side frame of the arch bar

type comprising a compression member and a tension member having their end portions united and with the extreme end portion outside of the point of intersection of their neutral axes inclined downwardly on an angle corresponding to the inclination of the tension member, and a pedestal jaw member secured in said angle and provided with downwardly flaring or diverging jaws.

30 9. A truck side frame of the arch bar type comprising a compression member and a tension member united at their ends and provided with downwardly flaring or diverging pedestal jaws symmetrically arranged relative to the point of intersection of the neutral axes of the tension and compression members.

35 10. A truck side frame of the arch bar type provided with pedestal jaws, a journal box fitting between said pedestal jaws, a pair of widely spaced horizontal lugs on said pedestal, a pair of coöperating vertical lugs on said journal box, and emergency means connecting said lugs.

40 In testimony whereof, I have hereunto set my hand.
